(57) **CLAIM**

The ornamental design for a network gateway, as shown and described.

DESCRIPTION

FIG. 1 is a top plan view of a network gateway showing my new design;

FIG. 2 is a left side elevation view thereof;

FIG. 3 is a front elevation view thereof;

FIG. 4 is a bottom plan view thereof;

FIG. 5 is a rear elevation view thereof;

FIG. 6 is a front perspective thereof;

FIG. 7 is a rear perspective view thereof;

FIG. 8 is right side elevation thereof; and,

FIG. 9 is a bottom perspective view thereof.

The broken lines immediately adjacent to the claimed areas represent the bounds of the claimed design while all other broken lines, including the broken lines depicting the entire bottom, are directed to environment. The broken lines form no part of the claimed design. Further, the wire frame lines shown throughout the views are intended to indicate surface contour and are not intended to be surface ornamentation.
